United States Patent

Des. 239,874

Patented May 11, 1976

239,874

TRANSPARENCY DISPLAY MODULE

Frederick M. Avery, Milwaukee, Wis., assignor to The Howard Company, Inc., Elm Grove, Wis.

Filed Sept. 9, 1974, Ser. No. 504,273

Term of patent 14 years

Int. Cl. D16—02

U.S. Cl. D16—15

Fig. 1

Fig. 2

Fig. 4

Fig. 3

FIG. 1 is a view in perspective of a transparency display module showing my new design;

FIG. 2 is a front elevational view thereof, the side opposite being plain and unornamented;

FIG. 3 is a top plan view thereof;

FIG. 4 is a right-side elevational view thereof; and

FIG. 5 is a left-side elevational view thereof.

I claim:

The ornamental design for a transparency display module, as shown and described.
